UNITED STATES PATENT OFFICE.

BELLE LOUISE CURTIS, OF BIRMINGHAM, ALABAMA.

PUZZLE.

1,289,681.

Specification of Letters Patent. Patented Dec. 31, 1918.

Application filed March 4, 1918. Serial No. 220,313.

To all whom it may concern:

Be it known that I, BELLE L. CURTIS, a citizen of the United States, residing at Birmingham, in the county of Jefferson and State of Alabama, have invented certain new and useful Improvements in Puzzles, of which the following is a specification.

This invention relates to games and toys, and more especially to puzzles; and the object of the same is to produce a puzzle illustrative of the naval hazards which are due to submarine warfare.

The invention comprises a game board of specific structure having a channel from start to finish typifying a tortuous sea course beset with dangers, and a game piece typifying a vessel rocked to and fro by the wind and waves as she proceeds along said course, seeking to avoid the hazards which 20 of course typify mines and submarines.

Details are brought out in the following specification, reference being made to the drawings, wherein:—

Figure 1 is a plan view of this game ready 25 to be played, and

Fig. 2 is a transverse section of Fig. 1 on the line 2—2 thereof with the cover applied and the game pieces removed.

The game board forming part of this 30 complete puzzle may well be a paste-board box about a foot in diameter and an inch deep, externally and internally painted or printed with appropriate colors and perhaps at proper points with flags or coats of arms 35 typifying the Allies which are supposed to be at war with that nation conducting a ruthless submarine warfare. The base or bottom of the box is numbered 1 in Fig. 2 and its rim is numbered 2, while the cover

40 numbered 3 in that view is shown as removed in Fig. 1. About half way of the depth of the box the same is provided with a horizontal partition 4 which is practically coincident with the area of the box excepting 45 as hereinafter specified. Paralleling the rim or outer wall 2 is an inner wall 5, and if both walls are circular this inner wall will define a retiring pocket 6 in which the game pieces are kept when not actually in play.

50 The two walls constitute the sides, and the partition 4 between said walls constitutes the bottom, of an annular course 7 which surrounds the pocket 6, and at one point this course is interrupted by a radial partition 55 8 which rises the full height of the outer wall or rim 2 of the box body. The bottom of the

course is inclined downward from both sides to the base of this partition 8, thereby producing on one side of said partition a starting pocket 9 and on the other side of the 60 partition a finishing pocket 10 which might be called the goal. Thereby is produced a course from start to finish, which course is irregular in that it is not straight, and this course is beset with hazards in the shape of 65 holes 11 and 12 through the bottom of the course into the chamber 13 below. Said holes may be of various shapes and disposition, and in Fig. 1 I have shown those numbered 11 as practically at the transverse center of the course 7, whereas those numbered 12 are alongside one wall or the other thereof. The result is that a path along the course is extremely tortuous, because any game piece which is moved along said path 75 is likely to fall through one of the hazards.

In the chamber beneath the partition 4 is a corral composed of two walls 15 and 16 which converge toward an opening 19 into the starting pocket 9, the corral thus underlying the retiring pocket 6 as indicated in dotted lines in Fig. 1. Other portions of the chamber 13 receive all game pieces dropping through the hazard-holes, and therefore the course 7 may be said to typify the 80 surface of the ocean along which sail the ships (game pieces) while the chamber typifies all that portion of the ocean beneath the surface and into which the ships sink when they strike a mine or are successfully 85 attacked by a submarine. Thus my improved game is illustrative of ruthless warfare, without the necessity of providing any element which typifies the submarine or mine itself. The game or puzzle may be played 90 in a number of ways. Let us assume that some of the game pieces or "pieces" as we will call them are dropped through any of the holes into the chamber 13 at starting. The player takes the device in hand and tilts 100 it in such manner that the pieces collect within the corral, and one by one they pass through the hole 19 into the starting pocket 9. The puzzle now is to so tilt the device 105 that this piece shall pass along the course 7 and avoid all hazards 11 and 12, finally reaching the finishing pocket or goal 10. This piece is now picked out and put into the retiring pocket 6 and the next piece is caused to move through the same irregular course, 110 and with the same end in view.

Another feature of my improved puzzle

is the provision of peculiar pieces for playing it. Three of such pieces are shown in Fig. 1, and one of them is broken away. I can best describe each by saying that its body is in the shape of a capsule 20, cylindrical for most of its length and having rounded extremities. In fact I have successfully used gelatin capsules for this purpose and in any event it may be advisable to have the body transparent. Around the center of the body I secure a band 21 which makes the circumference of the body at this point larger than elsewhere, and gives the entire device a peculiar tilting effect when we consider the weight 22 next to be mentioned. That is to say, the body may rest on the band 21, or on the band and one end or on the band and the other end; and whichever way it rests it will roll in an irregular manner when its support is tilted as described above. Said weight may well be a little shot or steel ball, sufficiently smaller that the inside of the body to permit it to roll freely from one end to the other; and the addition of this weight complicates the results which take place when the support is tilted, and renders the action of the game piece extremely erratic. I have shown three of these pieces and it may be well to color one white, another red, and another blue, or perhaps to inscribe on them the flags of the allied nations. When played as above suggested they will of course typify vessels which are to move over the course and avoid the hazards, and the winner of the game or the person to solve the puzzle is the one who successfully moves all three pieces along the course. However, in this and other respects I reserve the widest latitude, and details of structure and of play should be left to the manufacturer. It is quite possible to use pieces which are much simpler in construction such as buttons or checkers or perhaps merely balls or marbles; but I prefer pieces whose movements will be irregular and erratic so as to render it extremely difficult to move such pieces along an irregular course and avoid the hazards with which it is beset. The materials and proportions of all parts are not essential, and I have suggested that the capsule-body 20 of the piece be made transparent merely so that the rolling weight 22 therein can be observed, although this of course is not necessary.

Copies of this patent may be obtained for five cents each, by addressing the "Commissioner of Patents, Washington, D. C."

After the game is played the cover 3 is applied to keep the parts in place, ready for subsequent use, and this cover may also be useful in shipping the game. I have stated that I prefer the box shall be circular, but of course it could have other configuration without departing from the principle of the invention.

What is claimed as new is:—

1. In a puzzle, the combination with a game board comprising a flat bottom and an upstanding rim, an inner wall parallel to said rim, a horizontal partition underlying said wall and with it defining a retiring pocket and continued beyond this wall to the rim and between these elements defining a game course provided with hazard openings, and a radial wall connecting the inner wall with the rim at one point, the partition within said course being inclined downward in both directions to said radial wall to define a starting pocket on one side and a finishing pocket on the other side of said radial partition; of a movable game piece for use on said board, substantially as described. 80

2. In a puzzle, the combination with a circular game board comprising a flat bottom and an annular upstanding rim, an annular wall paralleling said rim, a horizontal partition underlying said wall and with it defining a retiring pocket and continued beyond this wall to the rim and between these elements defining an annular course, the partition throughout the length of said course being provided with hazard openings, a radial wall connecting the inner wall with the rim at one point, the partition within said course being inclined downward in both directions to said radial wall to define a starting pocket on one side and a finishing pocket on the other side of said radial partition, and converging walls beneath the partition defining a corral and leading to said starting pocket; of a movable game piece for use on said board, substantially as described. 90 95 100

In testimony whereof I affix my signature in presence of two witnesses.

BELLE LOUISE CURTIS.
